TYPEWRITING MACHINE

Filed Jan. 5, 1923

Patented May 26, 1925.

1,539,285

UNITED STATES PATENT OFFICE.

HARRY H. VICKERS, OF CORONA, NEW YORK, ASSIGNOR TO UNDERWOOD TYPEWRITER COMPANY, OF NEW YORK, N. Y., A CORPORATION OF DELAWARE.

TYPEWRITING MACHINE.

Application filed January 5, 1923. Serial No. 610,746.

To all whom it may concern:

Be it known that I, HARRY H. VICKERS, a citizen of the United States, residing in Corona, Long Island, in the county of 5 Queens and State of New York, have invented certain new and useful Improvements in Typewriting Machines, of which the following is a specification.

This invention relates to typewriting machines, and is herein illustrated as applied to an Underwood bookkeeping machine.

In certain classes of manifolding work, it is found desirable to omit certain items on the original sheet of a plurality of superposed work-sheets provided with interleaved carbons, and, at the same time, to make carbon impressions of the items on the remaining work-sheets. For example, 15 insurance companies, in filling out policies, make thereon certain entries including the name of the insured and make a carbon copy on a record-sheet which is used with successive policies until exhausted. While a policy and the record-sheet are superposed, 20 both the name of the insured and the address are typed. It is undesirable, however, to have the address appear on the policy.

In carrying out the invention, use may be made of a ribbon having the usual black 30 field and a white or blank field. Ordinarily the ribbon mechanism is so set as to vibrate the black field to the printing point during typing operations.

When the zone or column is reached in 35 which the typing is to be omitted on the outer sheet and ribbon copies are to be made on an inner or record sheet, the ribbon mechanism is automatically shifted to vibrate the white field to the printing point when 40 typing is effected. To this end, provision may be made of a special or color-controlling stop mounted on the carriage, and of such length as to be effective for as great a part of the carriage-travel as is necessary. 45 Upon movement of the carriage to the proper position, the color-controlling stop shifts the ribbon mechanism to make the white or blank field effective and holds the mechanism so shifted until the carriage passes 50 out of the zone, whereupon the ribbon mechanism is permitted to return to the position for typing in black.

It may be desired at times to have the 55 type impressions appear on the outer sheet in a zone or column in which typing is ordi-

narily effected through the white field of the ribbon. To this end, provision may be made in the automatic ribbon-controlling mechanism of a lever actuatable by a color-stop and an interponent normally actuatable by the 60 lever, but shiftable to a position to be free of said lever. For such shifting of the interponent, provision may be made of a special key and suitable means actuatable thereby.

A latch may also be provided to detain 65 said special or interponent-shifting key in actuated position to render the ribbon mechanism free of the automatic control by the carriage.

A latch-operating key may also be provided for moving the latch to ineffective 70 position.

Other features and advantages will hereinafter appear.

In the accompanying drawings,

Figure 1 is a skeleton perspective view, 75 showing the invention applied to so much of an Underwood bookkeeping machine as is necessary for the purpose of illustration.

Figure 2 is a fragmentary side elevation, 80 partly in section.

Figure 3 is a detail view, showing the color-indicating device at the front of the machine.

Upon the actuation of character-keys, not 85 shown, type-bars 11 are swung upwardly and rearwardly to cause types 12 thereon to strike through a ribbon 13 to make ribbon impressions on a work-sheet passing around a platen 14 journaled by means of 90 its axle 15 in a platen-frame forming part of a carriage 17, the latter being supported at its rear on a rail 18, for movement transversely of the machine.

When a type-bar 11 approaches the end 95 of its typing movement, a heel 19 thereon strikes a universal bar 20, forming part of a universal frame 21 supported at its rear end by a rocker 22, and forces the frame 21 rearwardly, thereby actuating escapement 100 mechanism, not shown, to cause the carriage 17 to take a step-by-step letter-feeding movement. Each rearward movement of the frame 21 also serves to lift a ribbon-vibrator 23, through the upper end of which the ribbon 13 is threaded, to position the ribbon 105 to be struck by one of the types at the printing line.

As herein disclosed, the ribbon 13 has an upper black field through which typing is 110

usually effected, and a lower white or blank field which may be brought to the printing line by giving the vibrator 23 an abnormal movement. For this purpose, provision is 5 made of a lever 24 pivoted at 25 and having a pivotal connection at its forward end with the lower end of the ribbon-vibrator 23. The rear arm of the lever 24 extends upwardly from the pivot 25 and is provided 10 at its right side with a pin 26, and at its left side with a pin 27 closer to the pivot 25 than the pin 26. A frame or shifter 28 is transversely slid able on the universal frame 21, and is provided with slots at its 15 sides, so that, when moved to its leftward position, the pin 26 will extend into the corresponding slot. When the parts are in such positions, rearward movement of the frame 28 with the universal frame 21 will 20 rock the lever 24 by means of the pin 26 and lift the ribbon-vibrator 23 to cause typing through the black upper field 29 of the ribbon.

When, however, the frame 28 is moved to 25 the right to cause the pin 27 to pass through the left-hand slot of the frame 28, movement of the universal frame 21 rearwardly will obviously cause a greater lifting of the vibrator 23 and cause the types, when operated, to strike the lower white field 30 of 30 the ribbon 13, thereby preventing ribbon impressions on the work-sheet lying to the rear of the ribbon. If, however, a plurality of superposed work-sheets with interleaved 35 carbons are in position on the platen, carbon copies of the typing will be effected on all of the work-sheets at the rear of the first, although no ribbon impressions are made on the first sheet.

40 According to the present invention, provision may be made of means for automatically controlling the position of the frame 28 to determine whether or not ribbon impressions shall be made on a work-sheet at 45 the rear of the ribbon 13. Preferably use is made of a special stop 31 having two forked members 32 to fit over a rack-bar 33 mounted on arms 34 extending rearwardly from the carriage 17. The two members 32 50 are at a plurality of letter-spaces apart, the spacing being sufficient to correspond to a column of the outer work-sheet in which no ribbon impressions are to be made, and the members 32 are connected by a member 55 35 having a rearwardly-extending flange 36. It should be noted that the rack 33 may be the usual rack-bar on which tabulator-stops are mounted, so as to co-operate with counter-stops 37 when the latter are lifted by 60 tabulator-keys, not shown.

Normally the frame 28 is connected with the lever 24 in the manner indicated in Figure 1, but, upon movement of the carriage into a zone corresponding to the position 65 of the controlling stop 31, the flange 36

will engage a dog 38 on a lever 39 and rock the latter about its pivot 40. This movement of the lever 39 draws upwardly a link 41 to act through an arm 42 to rock a shaft 43, mounted on brackets 44, against the 70 action of a helical spring 45 having one end connected with a fixed member 46 and the other connected with the shaft 43. The rocking movement of the shaft 43 is transmitted by means of an arm 47 on the shaft 43 and by a link 48 to a bell-crank 49 pivoted at 50 on a bracket 51. The forwardly-extending arm 52 of the bell-crank 49 projects under a pin or projection 53 on a vertical link 54 guided at its lower end 75 in a slot 55 formed in a plate 56 attached to a fixed part of the machine and pivoted at its upper end to an arm 57 fixed on a shaft 58. Such rocking of the shaft 58 is transmitted by means of an arm 59 thereon to 80 a link 60 connecting the upper end of the arm with the frame 28, and the link is pulled to the right to cause the frame 28 to engage the pin 27, so that, upon the next 85 operation of a type-bar 11, a type thereon 90 will act through the white ribbon field 30, and no ribbon impression will be effected by such typing.

It may be desirable at times to have ribbon impressions appear on the work-sheet 95 in a zone or column in connection with which the ribbon is ordinarily shifted to the white or blank field. To this end, provision may be made of a key 61, which, when 100 pressed rearwardly, acts through a link 62 to rock a lever 63 about its pivot 64 and against the action of a spring 65 connected at one end to the link 62 and at the other end to the lever 63. Such movement of the 105 lever 63 causes a cam 66 on the free end thereof to engage the lower end of the link 54 and force it forwardly in the slot 55 against the action of a spring 67 connected at one end to the link 54 and at the other end to the bracket 51, thus effecting a separation 110 between the pin 53 and the arm 52 of the bell-crank 49. It should be noted that the arm 52 is so shaped on its lower side as to facilitate the passage thereby, in an upward direction, of the pin 53 if the latter 115 is carried below said arm 52.

To hold the key 61 in its depressed or rearward position, provision may be made of a latch 68 to be pressed downwardly, 120 against the action of a spring 68^a, by a pin 69 on the link 62 as the link moves rearwardly, and to catch the pin 69 when the latter is carried past the projection 70 on the latch. Connected with the latch-proper, by means of a bridge 71, is a parallel part 72, and the latch is pivoted on a post 73 by a pivot or pivots passing through both the latch-proper 68 and the member 72. 125 To shift the latch 68 to release the key 61, provision is made of a special key 74 con- 130

nected with the member 72 in any suitable manner. As herein disclosed, the key 74 is shown as mounted on a shank 75, provided at its lower end with flanges to engage 5 on opposite sides of the member 72, the shank being held in position on the member 72 by means of a screw 76.

At its forward end the shaft 58 is provided with a color-signal 77, having thereon 10 a black field 78 and a white or blank field 79 to be exposed through a sight-opening 80 in a plate 81 to indicate the condition of the ribbon-controlling mechanism. As shown in Figure 1, the color-signal 77 is 15 provided with a substantially horizontal arm 82 which is urged in a downward direction by a spring 83 connected at its lower end to a fixed pin 84, the spring 83 tending to maintain the frame 28 in its normal position.

Preferably the dog 38 is provided with an inclined surface 85 to be engaged by the flange 36 on the stop 31, thus facilitating the actuation of the lever 39 by the stop 31. 25 In order to prevent interference by the dog 38 with the carriage 17 in the return movement of the latter, the dog 38 is mounted so as to be swung about a pivot 86 to ineffective position when struck by the flange 36 during the rearward movement of the carriage. Normally the dog 38 is held in effective position against a pin 87 on the lever 39 by means of a spring 88.

Variations may be resorted to within the 35 scope of the invention, and portions of the improvements may be used without others.

Having thus described my invention, I claim:

1. In a typewriting machine, in combination, a traveling carriage, a platen to support, at the printing line, a plurality of superposed work-sheets and interleaved carbons, types to press against the platen at the printing line to make ribbon impressions 45 on the outside work-sheet and carbon impressions on the other work-sheets, and carriage-controlled means to prevent impressions from being made on the outside work-sheet during part of the making of carbon copies on the other or inner work-sheets.

2. In a typewriting machine, in combination, a traveling carriage, a platen to support, at the printing line, a plurality of superposed work-sheets and interleaved carbons, types to press against the platen at the printing line to make ribbon impressions 55 on the outside work-sheet and carbon impressions on the other work-sheets, carriage-controlled means to prevent impressions from being made on the outside work-sheet during part of the making of carbon copies on the other or inner work-sheets in a certain part of the carriage travel, and means for relieving said preventing means from 60 control by the carriage to enable ribbon im-

pressions to be effected irrespective of the position of the carriage, when desired.

3. In a typewriting machine, in combination, a platen to support, at the printing line, a plurality of superposed work-sheets 70 and interleaved carbons, types to press against the platen at the printing line to make ribbon impressions on the outside work-sheet and carbon impressions on the other work-sheets, and means operated during typing without attention from the operator to prevent impressions from being made in predetermined columns of the outside work-sheet during the making of carbon copies on the other or inner work-sheets. 80

4. In a typewriting machine, in combination, a platen, types to co-operate with said platen at the printing point, a ribbon comprising an inked field and an uninked shielding field, ribbon-controlling means 85 normally acting to cause ribbon impressions to be made on an outer work-sheet during typing, and means operated by the travel of the carriage automatically to modify the action of the ribbon-controlling means to cause the uninked field to become effective at a predetermined point and so to prevent the making of impressions on the outer sheet.

5. In a typewriting machine, in combination, a platen, types to co-operate with said platen at the printing point, a ribbon comprising an inked field and an uninked shielding field, ribbon-controlling means 90 normally acting to cause ribbon impressions to be made on an outer work-sheet during typing, means operated automatically at a predetermined portion of the carriage travel to modify the action of the ribbon-controlling means to prevent the making of impressions, and manual means for rendering said automatic means ineffective. 95

6. In a typewriting machine, in combination, a platen, types to co-operate with said platen at the printing point, a ribbon comprising an inked field and an uninked shielding field, ribbon-controlling means 100 normally acting to cause ribbon impressions to be made on an outer work-sheet during typing, means operated by the travel of the carriage automatically to modify the action of the ribbon-controlling means to prevent the making of impressions, manual means for rendering said automatic means ineffective, and a latch acting to prevent the return 105 of said automatic means to effective condition.

7. In a typewriting machine, in combination, a platen, types to co-operate with said platen at the printing point, a ribbon comprising an inked field and an uninked shielding field, ribbon-controlling means 110 normally acting to cause ribbon impressions to be made on an outer work-sheet during typing, means operated by the travel of the 115

- carriage automatically to modify the action of the ribbon-controlling means to prevent the making of impressions, manual means for rendering said automatic means ineffective, a latch acting to prevent the return of said automatic means to effective condition, and a finger-piece to release said latch.

8. In a typewriting machine, in combination, a traveling carriage, a platen, a ribbon having an inked field and an uninked shielding field, ribbon-vibrator means normally presenting the inked field of the ribbon at the printing point, and controlling means shiftable by the carriage to cause said vibrator-means to present the uninked shielding field of the ribbon at the printing point and arranged to restore the ribbon-vibrator means to normal condition when released by the carriage.

20 9. In a typewriting machine, in combination, a traveling carriage, a platen, ribbon-vibrator means normally presenting one longitudinal field of a ribbon at the printing point, and means to modify the action of said vibrator means to cause another longitudinal field to be presented at the printing point, said modifying means comprising a pivotally-mounted arm, a depending link pivoted at its upper end to the free end of said arm, a carriage-actuated train of mechanism to lift said link, and manual means to swing said link to disconnect it from said train.

35 10. In a typewriting machine, in combination, a traveling carriage, a platen, ribbon-vibrator means normally presenting one longitudinal field of a ribbon at the printing point, and means to modify the action of said vibrator means to cause another longitudinal field to be presented at the printing point, said modifying means comprising a pivotally-mounted arm, a depending link pivoted at its upper end to the free end of said arm, a carriage-actuated train of mechanism to lift said link, manual means to swing said link to disconnect it from said train, a key, key-actuated means to swing said link to free the same from said train, and a latch for said key.

45 11. In a typewriting machine, in combination, a traveling carriage, a platen, ribbon-vibrator means normally presenting one longitudinal field of a ribbon at the printing point, and means to modify the action of said vibrator means to cause another longitudinal field to be presented at the printing point, said modifying means comprising a pivotally-mounted arm, a depending link pivoted at its upper end to the free end of said arm, a carriage-actuated lever, means operated by said lever to lift said link, manual means to swing said link to disconnect it from said lifting means, a key, key-actuated means to swing said link to free the same from said lifting means,

55 a latch for said key, and a second key for releasing said latch.

12. In a typewriting machine, in combination, a traveling carriage, a platen, types to press against the platen at the printing point to make ribbon impressions on the outer of two superposed work-sheets and a carbon impression on the inner sheet, and means for preventing the making of impressions on the outer sheet during typing in a predetermined column thereof, said preventing means including a carriage-operable member held in operated position during the passage of the carriage through said column, a second member normally actuatable by the first member, but shiftable to ineffective relation therewith, and a spring for holding the second member in effective relation with the first member.

70 13. In a typewriting machine, in combination, a traveling carriage, a platen, types to press against the platen at the printing point to make ribbon impressions on the outer of two superposed work-sheets and a carbon impression on the inner sheet, and means for preventing the making of impressions on the outer sheet during typing in a predetermined column thereof, said preventing means including a carriage-operable member held in operated position during the passage of the carriage through said column, a second member normally actuatable by the first member, but shiftable to ineffective relation therewith, and a spring for holding the second member in effective relation with the first member.

80 14. In a typewriting machine, in combination, a traveling carriage, a platen, types to press against the platen at the printing point to make ribbon impressions on the outer of two superposed work-sheets and a carbon impression on the inner sheet, and means for preventing the making of impressions on the outer sheet during typing in a predetermined column thereof, said preventing means including a carriage-operable member held in operated position during the passage of the carriage through said column, a second member normally actuatable by the first member, but shiftable to ineffective relation therewith, and a spring for holding the second member in effective relation with the first member.

90 15. In a typewriting machine, in combination, a traveling carriage, ribbon-vibrating means having a normal and a greater movement, means comprising a link pivoted at its upper end to vary the movement of said

95 100 105 110 115 120 125 130

ribbon-vibrating means, a pin on said link, a guide having a slot in which the lower end of said link extends, a spring to hold said link at one end of the slot, a lever having the free end of one of its arms underlying said pin, carriage-actuable means to operate said lever to lift said link, and means to shift said link to move the pin beyond the end of said arm, the arm being so shaped on its lower side that the pin may readily pass thereby in the upward direction.
